UNITED STATES PATENT OFFICE

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL APPARATUS

Continuation of application Serial No. 135,340, filed September 14, 1926. This application filed July 6, 1928. Serial No. 290,789.

My invention relates to electrical apparatus, and is particularly adapted for, though in no way limited to, railway traffic controlling apparatus.

5 The present case is a continuation of my copending application, Serial No. 135,340, filed September 14, 1926, for Electrical apparatus, in so far as the subject matter common to the two applications is concerned.

10 I will describe two forms of apparatus embodying my invention, and will then point out the novel features thereof in claims.

In the accompanying drawings, Figs. 1 and 1^a, are diagrammatic views which when placed end to end in the order named, show one form of apparatus embodying my invention. Figs. 2, 3, 4, 5 and 6, are views showing the phase relations and the polarities of the currents in the windings 5 and 6 of the 20 relays shown in Figs. 1 and 1^a. Figs. 7, 7^a and 7^b, when placed end to end in the order named, form a view showing a modified form 25 of the apparatus illustrated in Figs. 1 and 1^a and also embodying my invention. Figs. 8 to 17, inclusive, are views showing the phase 30 relations and polarities of the current in the windings of the relays shown in Figs. 7, 7^a and 7^b.

Referring first to Figs. 1 and 1^a, the reference characters 30 and 30^a, designate the track rails of a stretch of railway track along which traffic normally moves in the direction indicated by the arrows. These rails are divided by insulated joints 2 into a plurality 35 of track sections A—B, B—C, C—D, etc.

Each track section is provided with two relays designated by the reference characters H and K with appropriate exponents, each of which relays comprises two windings 5 and 6. 40 The windings 5 of the relays H and K for each section are connected across the track rails adjacent the entrance end of the section, and the windings 6 are constantly supplied with alternating current from the secondary 45 of a transformer designated by the reference character L with an exponent corresponding to the location. The primary of each transformer L is connected with a suitable source of alternating current which is not shown in 50 the drawings. Interposed between the track

rail 30^a and the winding 5 of each relay H is an asymmetric unit 19 which permits current to flow from the rail 30^a to the winding 5, but not in the reverse direction. Interposed between the rail 30 and the winding 5 of each relay K is a similar asymmetric unit 20 which permits current to flow from the rail 30 to this winding but not from the winding to the rail 30. Preferably an asymmetric unit 21 is connected in multiple with the winding 5 of each relay H to shunt out from this winding any current which passes through the associated unit 19 in the high resistance direction, and preferably an asymmetric unit 22 is connected in multiple with winding 5 of each relay K for a similar reason. It will be seen, therefore, that current of one polarity but not of the other flowing in the track rails of each section will pass through winding 5 of the relay K for such section, whereas current of the second polarity but not of the first will pass through winding 5 of relay H for the section. 55 60 65 70 75

The two relays for each section control the supply of current to the track rails for the section next in the rear from the adjacent transformer L. The manner in which this control is effected will best be understood by tracing the circuits and explaining the operation of the apparatus simultaneously. 80

As shown in the drawing, the section immediately to the right of point E is occupied by a train W, so that relays H^E and K^E are both de-energized. Alternating current is then supplied to the primary 27 of the track transformer T^E by a circuit which passes from the secondary of transformer L^E, through contact 14^b—14 of relay K^E, contact 10^b—10 of relay H^E, primary 27 of transformer T^E, contact 9—9^b of relay H^E, and contact 13—13^b of relay K^E to the secondary of transformer L^E. The current which is thus supplied to the primary of transformer T^E is of what I will term "reverse relative phase". The secondary circuit for transformer T^E is then from secondary 26, through an asymmetric unit 23, track rail 30, asymmetric unit 20, winding 5 of relay K^D, track rail 30^a, contact 11—11^b of relay K^E, contact 7—7^b of relay H^E, and a reactance 28 to the secondary 26 of transformer T^E. 85 90 95 100

Asymmetric unit 23 is so connected in this circuit that only what I will term the "negative half-wave" of the alternating current from transformer T^c can flow in the track rails of section D—E. In other words, the positive half-wave of this current is blocked by the unit 23. Since the asymmetric unit 19 associated with relay H^p prevents current of the negative half-wave flowing through winding 5 of this relay, it follows that relay H^p is de-energized. Unit 20 permits current of the negative half-wave to flow in winding 5 of relay K^p , however, and so this relay is energized. Relay K^p is energized in the reverse direction because the relative phase of the current in its winding 5 is reversed with respect to the phase of the current in its winding 6. The conditions existing in the windings of relays H^p and K^p are illustrated in Figs. 2 and 6. As shown in Fig. 2, full-wave alternating current of normal relative phase is supplied to winding 6 of each of these relays, whereas as shown in Fig. 6, only the negative half-wave of alternating current of reverse relative phase is supplied to the track rails, and so relay K^p is energized in the reverse direction but relay H^p is de-energized.

Considering now the supply of current to the rails of section C—D, the circuit for the primary 27 of transformer T^p is from the secondary of transformer L^p , through contact 13^c—13 of relay K^p , contact 9^b—9 of relay H^p , primary 27 of transformer T^p , contact 10—10^b of relay H^p and contact 14—14^c of relay K^p to the secondary of transformer L^p . Due to the energization of relay K^p in the reverse direction, the contacts 9, 10, 13 and 14 have acted as a pole-changer to reverse the relative phase of the current in the primary 27 of transformer T^p , so that current of normal relative phase is supplied to section C—D by this transformer. The track circuit for section C—D is from secondary 26 of transformer T^p , through asymmetric unit 23, upper track rail 30, asymmetric unit 20, winding 5 of relay K^c , lower track rail 30^a, contact 11—11^c of relay K^p , contact 7—7^b of relay H^p , and reactance 28 to the secondary 26 of transformer T^p . The unit 23 permits only the negative half-wave to flow in this circuit, and, consequently, winding 5 of relay K^c is supplied with the negative half-wave of alternating current of normal relative phase, so that this relay is energized in the normal direction. Relay H^c is de-energized because the asymmetric unit 19 prevents the negative half-wave of alternating current from reaching winding 5 of this relay. The conditions in the windings of relays H^c and K^c are indicated in Figs. 2 and 5, from which it will be apparent that the relay K^c is energized in the normal direction.

Considering now track section B—C, the primary circuit for transformer T^c is from the secondary of transformer L^c , through

contact 14^a—14 of relay K^c , contact 10^b—10 of relay H^c , primary 27 of transformer T^c , contact 9—9^b of relay H^c , and contact 13—13^a of relay K^c to the secondary of transformer L^c . This current is of reverse relative phase. The secondary circuit for transformer T^c is from secondary 26, through reactance 28, asymmetric unit 24, lower track rail 30^a, asymmetric unit 19, winding 5 of relay H^p , upper track rail 30, contact 8—8^b of relay H^c , and contact 12—12^a of relay K^c , to the secondary 26 of transformer T^c . The asymmetric unit 24 in this circuit transmits the positive half-wave but not the negative half-wave, and so the asymmetric unit 20 associated with relay K^p prevents this current from reaching winding 5 of that relay. The conditions in the windings of relay H^p are indicated in Figs. 2 and 4, that is, winding 5 of this relay receives the positive half-wave of alternating current of reverse relative phase, so that this relay is energized in the reverse direction.

Considering now the supply of current to the rails of section A—B, the primary circuit for transformer T^b is from the secondary of transformer L^b , through contact 9^c—9 of relay H^b , primary 27 of transformer T^b , contact 10—10^c of relay H^b to the secondary of transformer L^c . This current is of normal relative phase. The secondary circuit for transformer T^b is from secondary 26, through reactance 28, asymmetric unit 24, lower track rail 30^a, asymmetric unit 19, winding 5 of relay H^a , upper track rail 30, and contact 8—8^c of relay H^b to secondary 26 of transformer T^b . The symmetric unit 24 transmits the positive half-wave but blocks the negative half-wave, and so the current in this circuit reaches winding 5 of relay H^a but not winding 5 of relay K^a . Inasmuch as winding 5 of relay H^a receives current of normal relative phase, this relay is energized in the normal direction. The conditions in the windings of the relays H^a and K^a are indicated in Figs. 2 and 3 of the drawings, from which it will be seen that relay K^a is de-energized because the negative half-wave is blocked, and that relay H^a is energized in the normal direction because the current supplied to its winding 5 is of normal relative phase.

The current supplied to the section to the left of point A has the same characteristics as that supplied to section A—B. The primary circuit for transformer T^a is from the secondary of transformer L^a , through contact 9^a—9 of relay H^a , primary 27 of transformer T^a and contact 10—10^a of relay H^a to the secondary of transformer L^c . Current flows from the secondary 26 of transformer T^a , through reactance 28, asymmetric unit 24, to the lower track rail 30^a and from the upper track rail 30, through contact 8—8^a of relay H^a , to the secondary 26 of transformer T^a . It will be seen, therefore, that the positive

half-wave of an alternating current of normal relative phase is supplied to the rails of the section to the left of point A.

The relays H and K may be employed to control traffic governing means of any desired type. As here shown, this traffic governing means is in the form of a wayside signal located at the entrance end of each section and designated by the reference character S with an exponent corresponding to the location. Each signal comprises an upper group of lamps 3, and a lower group of lamps 4, and each group includes a green lamp G, a yellow lamp Y, and a red lamp R.

Referring particularly to signal S^E, inasmuch as both relays H^E and K^E are de-energized, the two red lamps R are lighted, and all other lamps are extinguished. The circuit for the red lamp R of the upper group 3 is from the secondary of transformer L^E, through contact 15—15^b of relay H^E, contact 17—17^b of relay K^E, lamp R of group 3, to the secondary of transformer L^C. The circuit for lamp R of group 4 is from the primary of transformer L^E, through contact 15—15^b of relay H^E, contact 18—18^b of relay K^E, and lamp R to the secondary of transformer L^E. Signal S^E, therefore, indicates "stop".

Referring now to signal S^D, lamp Y of the upper group 3 is lighted, the circuit being from the secondary of transformer L^D, through contact 15—15^b of relay H^D, contact 17—17^c of relay K^D, lamp Y of upper group 3, to the secondary of transformer L^D. Lamp R of the lower group 4 is lighted, its circuit being from the secondary of transformer L^D, through contact 15—15^b of relay H^D, contact 18—18^c of relay K^D, and lamp R of the lower group 4 to the secondary of transformer L^C. Signal S^D, therefore, indicates "proceed, prepared to stop at next signal".

Referring to signal S^C, lamp Y of the upper group is lighted, the circuit being from the secondary of transformer L^C, through contact 15—15^b of relay H^C, contact 17—17^a of relay K^C, and lamp Y of upper group 3 to the secondary of transformer L^C. Lamp Y of the lower group is also lighted, its circuit being from the secondary of transformer L^C, through contact 15—15^b of relay H^B, contact 18—18^a of relay K^C, and lamp Y of group 4 to the secondary of transformer L^C. Signal S^C, therefore, indicates "proceed, prepared to stop at second signal in advance".

Considering signal S^B, the lamp G of the upper group is lighted, the circuit being from the secondary of transformer L^B, through contact 15—15^c of relay H^C and lamp G to the secondary of transformer L^C. Lamp Y of the lower group is lighted, its circuit being from the secondary of transformer L^B, through contact 16—16^c of relay H^B, and lamp Y of group 4 to the secondary of transformer L^B. It follows that signal S^B indicates "proceed, prepared to slow down at next signal".

Considering signal S^A, lamp G of the upper group is lighted, the circuit for this lamp being from the secondary of transformer L^A, through contact 15—15^a of relay H^A, and lamp G of upper group 3, to the secondary of transformer L^B. Lamp G of the lower group is also lighted, the circuit for this lamp being from the secondary of transformer L^A, through contact 16—16^a of relay H^A, and lamp G of the lower group 4, to the secondary of transformer L^A. Signal S^A, therefore, indicates "proceed".

Referring now to Figs. 7, 7^a and 7^b, in the form of apparatus here shown, each of the sections A—B, B—C, C—D, D—E, E—F, F—M, M—P, and P—Q, is provided with two relays H and K similar to the corresponding relays described in connection with Figs. 1 and 1^a. In the present embodiment of my invention, however, winding 5 of each of the relays H and K is connected directly with the track rails of the associated section. Winding 6 of each relay H is supplied with alternating current from the associated transformer L through an asymmetric unit 34; a second asymmetric unit 35 being connected across the terminals of the relay. In similar manner current is supplied to winding 6 of relay K through an asymmetric unit 36; an additional asymmetric unit 37 being connected across the terminals of the relay. It will be plain, therefore, that each winding 6 is supplied only with half waves of one polarity, and the parts are so proportioned that current flows in one direction through winding 6 of each relay H and in the same direction but of opposite phase through winding 6 of each relay K. It follows that full wave alternating current in the track rails will energize relays H and K in opposite directions. The currents in windings 6 of relays H and K are illustrated in Figs. 8 and 9, respectively.

In addition to the track transformer T, each section is provided with a second transformer designated by the reference character V with an exponent corresponding to the location and operating at times to supply current to the track rails in parallel with the associated transformer T.

Each section is also provided with a track-way signal S, which in the form here shown comprises nine lamps designated by the reference characters 58 to 66, inclusive, and each arranged to display a distinctive signal indication when energized.

As shown in the drawing, the section immediately to the right of point Q is occupied by a train W. Relays H^Q and K^Q are therefore de-energized and lamp 58 of signal S^Q is lighted, the circuit for this lamp passing from the right-hand terminal of the secondary of transformer L^Q, over contact 45—45^b of relay H^Q, contact 55—55^b of relay K^Q, and lamp 58 of signal S^A, back to the mid-point

of the secondary of transformer L^Q . Under these conditions, also, a circuit is completed for the primary 27 of transformer T^Q which may be traced from the right-hand terminal of the secondary of transformer L^Q , through contact 51-51^b of relay K^Q , contact 43-43^b of relay H^Q , and primary 27 of transformer T^Q , back to the mid-point of the secondary of transformer L^Q . The secondary 26 of transformer T^Q is now connected with the track rails over a circuit which may be traced from the right-hand terminal of this secondary, through impedance 28, contact 42-42^b of relay H^Q , contact 48-48^b of relay K^Q , and asymmetric unit 39 to rail 30 of section $P-Q$, and from rail 30^a of this section back to the left-hand terminal of secondary 26 of transformer T^Q . Under the conditions just described, alternating current of normal relative phase is supplied to the rails of section $P-Q$, but since asymmetric unit 39 is interposed in the secondary circuit of transformer T^Q , only the positive half waves of this current flow in the rails of section $P-Q$, as shown in Fig. 10.

Referring now to the apparatus located at point P , the positive half waves of alternating current of normal relative phase supplied to the rails of section $P-Q$ energize relay K^P in the normal direction, but this current does not energize relay H^P because it flows during the intervals that winding 6 of relay H^P is de-energized, so that the latter relay allows its contacts to assume their middle positions. A circuit is therefore completed for lamp 59 of signal S^P , over contact 45-45^b of relay H^P and contact 55-55^a of relay K^P , so that lamp 59 of signal S^P is lighted. A circuit is now closed from the left-hand terminal of the secondary of transformer L^P , through contact 51-51^a of relay K^P , contact 43-43^b of relay H^P and primary 27 of transformer T^P , back to the mid-point of the secondary of transformer L^P . The secondary 26 of transformer T^P is now connected with the rails of section $M-P$ through contact 42-42^b of relay H^P , contact 48-48^a of relay K^P and asymmetric unit 38. The rails of section $M-P$ are therefore supplied with only the negative half waves of alternating current of reverse relative phase. This current is shown diagrammatically in Fig. 11.

Relay H^M is de-energized, but relay K^M is energized in the reverse direction by the current flowing in section $M-P$. A circuit is completed for lamp 60 of signal S^M , over contact 45-45^b of relay H^M and contact 55-55^c of relay K^M , so that this lamp is lighted. A primary circuit is now closed for transformer T^M , from the left-hand terminal of the secondary of transformer L^M , over contact 51-51^c of relay K^M , contact 43-43^b of relay H^M , and primary 27 of transformer T^M , back to the mid-point of the secondary of transformer L^M . The sec-

ondary 26 of transformer T^M is connected with the rails of section $F-M$ over a circuit including contact 42-42^b of relay H^M , contact 48-48^c of relay K^M , and asymmetric unit 39, so that the rails of section $F-M$ are now supplied with only the positive half waves of alternating current of reverse relative phase, as shown in the diagram, Fig. 12.

At point F , therefore, relay H^F is energized in the normal direction, but relay K^F is de-energized. Under these conditions, a circuit is completed, to light lamp 61 of signal S^F over contact 45-45^a of relay H^F and contact 56-56^b of relay K^F . The primary circuit of transformer T^F is now completed from the left-hand terminal of the secondary of transformer L^F , over contact 52-52^b of relay K^F , contact 43-43^a of relay H^F and primary 27 of transformer T^F , back to the mid point of the secondary of transformer L^F . The secondary 26 of transformer T^F is connected with the rails of section $E-F$ over contact 42-42^a of relay H^F and contact 50-50^b of relay K^F . It will be noted that neither of the asymmetric units 38 or 39 at point F is included in the secondary circuit for transformer T^F , so that full wave alternating current of reverse relative phase is supplied to the rails of section $E-F$, as shown in Fig. 13.

Considering next the apparatus located at point E , the current now flowing in the rails of section $E-F$ energizes relay H^E in the normal direction and energizes relay K^E in the reverse direction so that a circuit is completed for lamp 62 of signal S^E over contact 45-45^a of relay H^E and contact 56-56^c of relay K^E . Furthermore, a primary circuit is closed for transformer T^E from the left-hand terminal of the secondary of transformer L^E over contact 52-52^c of relay K^E , contact 43-43^a of relay H^E , and primary 27 of transformer T^E to the mid-point of the secondary of transformer L^E . A circuit is also completed for transformer V^E , which circuit may be traced from the right-hand terminal of the secondary of transformer L^E , through contact 53-53^c of relay K^E , contact 44-44^a of relay H^E , and primary 33 of transformer V^E , back to the mid-point of the secondary of transformer L^E . The secondary 26 of transformer T^E is now connected with the rails of section $D-E$ over contact 42-42^a of relay H^E , contact 50-50^c of relay K^E and asymmetric unit 39. The positive half waves of alternating current of reverse relative phase are therefore supplied to the rails of section $D-E$. Furthermore, the secondary 32 of transformer V^E is connected, through impedance 90, contact 41-41^a of relay H^E , contact 47-47^c of relay K^E , and asymmetric unit 69, with the rails of section $D-E$. The positive half waves of alternating current of normal relative phase are therefore supplied to the rails of section

120
125
130

D—E and the current in this section may be represented by the diagram, Fig. 14.

At point D, relays H^D and K^D are both energized in the normal direction and a circuit is completed for lamp 63 of signal S^D , over contact 45—45^a of relay H^D , and contact 56—56^a of relay K^D . The primary circuit for transformer T^D may be traced from the right-hand terminal of the secondary of transformer L^D , through contact 52—52^a of relay K^D , contact 43—43^a of relay H^D and primary 27 of transformer T^D back to the mid-point of the secondary of transformer L^D . The secondary of transformer T^D is now connected with the rails of section C—D through contact 42—42^a of relay H^D , contact 50—50^a of relay K^D and asymmetric unit 38. The rails of section C—D are therefore supplied with the negative half waves of alternating current of normal relative phase as indicated in Fig. 15.

The current thus supplied to the rails of section C—D energizes relay H^C in the reverse direction, but relay K^C is de-energized, and a circuit is completed for lamp 64 of signal S^C over contact 45—45^c of relay H^C and contact 57—57^b of relay K^C . Current now flows from the right-hand terminal of the secondary of transformer L^C over contact 43—43^c of relay H^C , and primary 27 of transformer T^C to the mid-point of the secondary of transformer L^C . Current is also supplied to transformer V^C over a circuit which may be traced from the left-hand terminal of the secondary of transformer L^C , through contact 54—54^b of relay K^C , contact 44—44^c of relay H^C , and primary 33 of transformer V^C , back to the mid-point of transformer L^C . The secondary 26 of transformer T^C is now connected with the rails of section B—C over contact 42—42^c of relay H^C and contact 49—49^b of relay K^C and asymmetric unit 38. Furthermore, the secondary 32 of transformer V^C is now connected with the rails of section B—C over contact 40—40^c of relay H^C , contact 46—46^b of relay H^C and asymmetric unit 68. The rails of section B—C are therefore supplied with only the negative half waves of alternating currents of both normal and reverse phases as indicated by Fig. 16.

Considering now the apparatus at point B, the current thus supplied to the rails of section B—C energizes both relays H^B and K^B in the reverse direction and a circuit is then completed for lamp 65 of signal S^B over contact 45—45^c of relay H^B and contact 57—57^c of relay K^B . A primary circuit is closed for transformer T^B from the right-hand terminal of the secondary of transformer L^B , through contact 43—43^c of relay H^B , and primary 27 of transformer T^B to the mid-point of the secondary of transformer L^B . The secondary 26 of transformer T^B is connected with the rails of section A—B over

contact 42—42^c of relay H^B , and contact 49—49^c of relay K^B . It should be observed that neither of the asymmetric units 38 or 39 is included in this secondary circuit so that full wave alternating current of normal relative phase is now supplied to the rails of section A—B as shown in Fig. 17.

Current thus supplied to the rails of section A—B energizes relay H^A in the reverse direction and energizes relay K^A in the normal direction. A circuit is then completed for lamp 66 of signal S^A over contact 45—45^c of relay H^A and contact 57—57^a of relay K^A . Primary 27 of transformer T^A is now connected with the right-hand portion of the secondary of transformer L^A , over contact 43—43^a of relay H^A . The secondary 26 of transformer T^A is connected, through contact 42—42^a of relay H^A and contact 49—49^a of relay K^A , directly with the rails of the section to the left of point A so that the rails of this section are supplied with full wave alternating current of normal relative phase as shown in Fig. 17.

It will be seen from the foregoing that with the arrangement of apparatus shown in Figs. 7, 7^a and 7^b, I have provided a system of railway signaling in which nine separate and distinct indications are available without the necessity of providing line wires between locations.

It should be pointed out that although I have illustrated relays H and K as three-position two-element relays, the functions of these parts could equally well be performed by two-position relays of the usual neutral type, the necessary modifications of the circuits being obvious from an inspection of the drawing, without further explanation.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, two relays each having two windings and each being selectively responsive to the phase relation of currents in its windings, means for constantly supplying one winding of each relay with alternating current of fixed relative phase, means for supplying the second windings with only the positive or only the negative half waves of alternating current of one phase or the other, means associated with said relays for permitting current of one polarity but not of the other to flow in the second winding of one relay and for permitting current of the second polarity but not of the first to flow in the second winding of the other relay, and signaling means controlled by said relays.

2. In combination, two relays each hav-

ing two windings and each being selectively responsive to the phase relations of currents in its windings, means for constantly supplying one winding of each relay with alternating current of fixed relative phase, means for supplying the second windings with only the positive or only the negative half waves of alternating current of one phase or the other, an asymmetric unit in series with the second winding of one relay for permitting current of one polarity but not of the other to flow through such winding, an asymmetric unit in series with the second winding of the other relay for permitting current of the second polarity but not of the first to flow through such winding, and signaling means controlled by said relays.

3. In combination, a relay having two windings and selectively responsive to the phase relation of currents in said windings, means for constantly supplying one of said windings with alternating current of fixed phase, a circuit for the second winding including means for at times supplying only one half wave of alternating current of normal or reverse relative phase and for at other times supplying the other half waves of alternating current, means for permitting the first said half waves but not the second to flow through said second winding, other apparatus included in said circuit and responsive to said second half waves of alternating current, and signaling means controlled by said relay and by said other apparatus.

35. 4. In combination, a stretch of railway track divided into sections, two relays for each section having two windings and each being selectively responsive to the phase relation of currents in its windings, means for constantly supplying one winding of each relay with alternating current of fixed relative phase, the second winding of each relay being connected with the rails of the associated section, means controlled by the two relays for each section for supplying the rails of the section in the rear with only the positive or only the negative half waves of alternating current of one phase or the other, means associated with each section for permitting current of one polarity but not of the other to flow in the second winding of one relay for the section and for permitting current of the second polarity but not of the first to flow in the second winding of the other relay for the section, and signalling means for said sections controlled by said relays.

5. In combination, a stretch of railway track divided into sections, two relays for each section each having two windings and each being selectively responsive to the phase relation of currents in its windings, means for constantly supplying one winding of each relay with alternating current of fixed relative phase, the second winding of each relay being connected with the rails of the associated sec-

tion, means controlled by the two relays for each section for supplying the rails of the section in the rear with only the positive or only the negative half waves of alternating current of one phase or the other, an asymmetric unit interposed between the track rails of each section and the second winding of one relay for such section for permitting current of one polarity but not of the other to flow through such winding, an asymmetric unit interposed between the track rails of each section and the second winding of the other relay for such section for permitting current of the second polarity but not of the first to flow through such winding, and signaling means for said sections controlled by said relays.

6. In combination, two electro-responsive devices each having two windings and each being selectively responsive to the phase relation of the currents in its windings, means for constantly supplying one winding of each device with alternating current of fixed relative phase, means for supplying the second windings with only the positive or only the negative half-waves of alternating current of one phase or the other, and means associated with said devices for permitting current of one polarity but not of the other to flow in the second winding of one device and for permitting current of the second polarity but not of the first to flow in the second winding of the other device.

7. In combination, two electro-responsive devices each having two windings and each being selectively responsive to the phase relation of the currents in its windings, means for constantly supplying one winding of each device with alteranting current of fixed relative phase, means for supplying the second windings with only the positive or only the negative half-waves of alternating current of one phase or the other, an asymmetric unit in series with the second winding of one device for permitting current of one polarity but not of the other to flow through such winding, and an asymmetric unit in series with the second winding of the other device for permitting current of the second polarity but not of the first to flow through such winding.

8. In combination, a stretch of railway track divided into sections, two relays for each section each capable of energization in normal and reverse direction, means controlled by the relays of each section for supplying the rails of the section next in the rear with only the positive or only the negative half-waves of alternating current of one phase or the other, and signaling means for said sections controlled by said relays.

9. In combination, a stretch of railway track divided into sections, two relays for each section and responsive selectively to the phase and relative polarity of current flowing in the track rails of the section, means con-

trolled by the relays for each section for supplying the rails of the section in the rear with only the positive or only the negative half-waves of alternating current of one phase or the other, and signaling means for said sections controlled by said relays.

10. In combination, a stretch of railway track divided into sections, two relays for each section and responsive to the relative phase and the polarity of current in the track rails of the section, means operating when the two relays for a section are de-energized to supply the rails of the section next in the rear with the positive half-waves of an alternating current of normal relative polarity, means operating when the first relay for a section is de-energized and the second relay for the section is energized in reverse direction for supplying the rails of the section next in the rear with the positive half-waves of alternating current of reverse relative polarity, means operating when the first relay of a section is de-energized and the second relay for the section is energized in normal direction for supplying the rails of the section next in the rear with the negative half-waves of alternating current of reverse relative polarity, means operating when the second relay of a section is de-energized and the first relay for the section is energized in normal direction for supplying the rails of the section next to the rear with the negative half-waves of alternating current of normal relative polarity, and signaling means for the section controlled by said relays.

11. In combination, an electro-responsive device of two windings and selectively responsive to the phase relation of currents in said windings, means for constantly supplying one of said windings with alternating current of fixed phase, a circuit for the second winding including means for at times supplying only one half-wave of alternating current of normal or reverse relative polarity and for at other times supplying the other half-waves of alternating current, means for permitting the first said half-waves but not the second to flow through said second winding, and other means included in said circuit and responsive to said second half-waves of alternating current but not to said first half-waves.

12. In combination, a stretch of railway track divided into sections, two relays H and K for each section each having two windings and each being selectively responsive to the phase relation of currents in its windings, means for constantly supplying one winding of each relay with alternating current of fixed relative phase, means for connecting the second winding of each relay with the rails of the associated section through asymmetric units which permit the positive half-wave but not the negative half-wave to flow through relay H and which permit the negative half-

wave but not the positive half-wave to flow through relay K, means controlled by the contacts of the relays for each section for supplying current of normal relative phase to the rails of the section in the rear when relay H is energized in the reverse direction and relay K is de-energized, and also when the relay H is de-energized and relay K is energized in the reverse direction, and for supplying current of reverse relative phase to the rails of the section in the rear when both relays are de-energized and also when relay K is energized in the normal direction and relay H is de-energized, means for blocking the negative half-wave of the alternating current supplied to the rails of a section when the relay H is energized in the reverse direction and relay K is de-energized as well as when relay H is de-energized and relay K is energized in the normal direction, and means for blocking the positive half-wave of the alternating current supplied to a section when relay H is de-energized and relay K is energized in the reverse direction as well as when both relays H and K are de-energized.

13. In combination, a stretch of railway track divided into sections, two relays for each section each having two windings and each being selectively responsive to the phase relation of currents in its windings, means for constantly supplying one winding of each relay with alternating current of fixed relative phase, means for connecting the second winding of each relay with the rails of the associated section through asymmetric units which permit current of one polarity or the other to flow through the second winding of one relay and current of the second polarity but not of the first to flow through the second winding of the other relay, means controlled by the relays of each section for supplying alternating current of one relative phase or the other to the track rails of the section next in the rear, and means controlled by the relays of each section for blocking either the positive half-wave or the negative half-wave of the current thus supplied to the rails of the section next in the rear.

In testimony whereof I affix my signature.

HOWARD A. THOMPSON.
